United States Patent Office

Des. 203,525
Patented Jan. 18, 1966

203,525

BOAT ANCHOR

Charles B. Hutton, Rte. 4, Monticello, Ind.

Filed May 12, 1965, Ser. No. 85,231

Term of patent 14 years

(Cl. D71—1)

Fig. 1.

Fig. 2.

Fig. 3.

Fig. 4.

FIG. 1 is a perspective view, somewhat enlarged, of a boat anchor, showing my new design.

FIG. 2 is a front elevational view thereof.

FIG. 3 is a side elevational view thereof.

FIG. 4 is a bottom plan view thereof.

The portions shown in broken line are included for illustrative purposes only.

I claim:

The ornamental design for a boat anchor, as shown and described.
